INVENTOR-

George F. Voight

UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

LATH SPACER.

Application filed March 22, 1924. Serial No. 701,204.

My invention relates to improvements in a lath spacer in which a metal spacing clip is slidably carried on the forward end of an ordinary nail and cooperable therewith for securing wire lath outstandingly to the wall sheathing of a stuccoed building, although also useful for other purposes.

One of the objects of the present invention is the provision of a lath spacer comprising a spacing clip normally frictionally locked on the forward end of a nail, but vertically slideable thereon when disposed in engagement with the wall sheathing into which the nail is operatively driven.

15 A further object is the provision of a lath spacer projectable through the mesh of the lath in its application thereto for attaching the lath to the wall sheathing.

20 A still further object is the provision of a spacing clip embodying an intermediate vertically disposed spacing member terminating at its lower end in a horizontally disposed supporting base provided with an opening, and terminating at its upper end 25 in a horizontally disposed lath seat provided with an opening disposed in vertical axial alignment with said first named opening, the openings adapted to receive a nail for normally locking the clip thereon.

30 A further object is the provision of a lath retaining lip at the intersection of the lath seat and intermediate member.

35 A still further object is the provision of an extension on the free end of the lath seat for forming a clinching cap for operatively engaging and binding the reinforcing lath down permanently on the lath seat.

40 With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

45 In the accompanying drawings—

50 Figure 1 is a side elevation of a lath spacer constructed in accordance with my invention disposed in engagement with a fragmental portion of wall sheathing pre-

paratory to driving it thereinto, and a cross 55 section of wire lath in engagement with the spacer;

56 Figure 2 is a view similar to the one preceding but with the spacing clip shown in 60 sectional elevation;

65 Figure 3 is a side elevation of the device in its permanent position after being driven into the wall sheathing, the latter shown in sectional elevation, and a cross section of wire lath secured by the spacer;

70 Figure 4 is a plan view of the spacer and fragmental portions of the wall sheathing and lath;

75 Figure 5 is a view on line 5'-5', Fig. 1;

Figure 6 is a view on line 6'-6', Fig. 1;

Figure 7 is a perspective view of the 80 spacing clip detached from the nail;

Figure 8 shows a length of wire from which the spacing clip is formed; and

85 Figure 9 is a side elevation of a modification of the spacing clip attached to the forward end of a nail, and a cross section of the wire lath.

90 Referring to the drawings in detail, throughout which like reference characters 80 designate like parts:

95 The numeral 1 designates a representation of the usual wall sheathing forming the stucco backing of a stuccoed structure, which is faced off with the usual building paper 2.

100 The wall sheathing 1, which may be secured across the face of the ceiling joists and floor joists as well as to the perpendicular wall studs of the structure, is preferably laid in close jointed order to provide 90 an uninterrupted surface for the paper 2.

105 3 designates my improved lath spacer, which comprises a spacing clip 4 carried normally on the forward end of a nail 5, the latter comprising the usual shank 6 and head 7, and the spacing clip comprising a strip of flat wire bent to form, beginning at one end, first, a supporting base 8 disposed in a plane at right angles with the shank 6; thence extending upwardly along one side of the shank 6 thereby forming an intermediate or spacing member 9; thence folded double and extending outwardly with an upward curve forming a retaining lip 10; thence extending from the base of said retaining lip at right angles across the axis of the shank 6 thereby forming a lath seat 11;

thence curving upwardly in an arcuated loop and recrossing the axis of the shank at a distance above the lath seat 11 to form a clinching cap 12; and thence terminating in 5 a short downwardly extending locking lip 13 over-hanging the retaining lip 10.

The members 8, 11 and 12 are provided with apertures 14, 15 and 16, respectively, through which projects the shank 6, and by 10 means of which the clip 4 is mounted on the shank.

The openings or apertures 14, 15, 16, are preferably made large enough in relation to the shank 6, so that the shank may normally

15 slide readily along therethrough, but are intended to be disposed sufficiently out of alignment with each other so that the shank will bind against the margin of one or more of them and thereby cause the clip to become locked on the shank against accidental movement relative thereto, but vertically slidable thereon when the base 8 engages the face of the wall sheathing into which the shank is operatively driven. However, if so 20 preferred, one or more of the openings may be made to provide a relative close fit around and against the periphery of the shank and thereby normally lock the clip thereon; this being particularly true of the lower opening 25 14, which may be sufficiently restricted diametrically to provide a snug fit against the shank for holding the clip while the other two openings may provide a comparatively tight fit around the shank and permit the 30 latter to move freely therethrough.

35 17 designates a wire forming a portion of the wire lath employed in stucco construction for reinforcing the stucco composition and holding it against the side of the wall 40 sheathing, which wire lath may comprise any suitable net-work of wire, and which my improved spacers are adapted to secure to the sheathing in outstanding relation thereto.

45 To apply the lath spacer for securing the lath to the wall sheathing, the retaining lip 10 is hooked under the wire 17 with the forward end of the shank 6 disposed in engagement with sheathing 1 (see Figs. 1 and 2), 50 after which the shank is driven forward into the sheathing until the head 7 engages the clinching cap 12 and causes it to bend at the curve 18 and more downwardly with the head and firmly engage and bind the wire 17 down against the lath seat 11 (see Fig. 3).

The locking lip 13 is intended to cooperate with the retaining lip 10 for holding the wire 17 on the lath seat 11; if preferred, however, the locking lip 13 may be omitted and

the retaining lip alone depended on for retaining the wire on its seat.

In the modified form of the invention as shown in Fig. 9, the retaining lip 10 is omitted and the locking lip 13 only employed for confining the lath wire on seat 11.

As the primary function of the building paper 2 is to water-proof the wall sheathing 1, and may be considered to form a part thereof, the terms "sheathing" and "wall sheathing" where the same appear in this 70 specification, are to be taken to include the paper.

I claim:

1. In means of the character described, a spacing clip having a spacing member extending parallel with a cooperating nail shank, the lower end of said spacing member terminating in a supporting base penetrated by said shank, the upper end of said spacing member extending into a lath seat also penetrated by said shank, said lath seat and supporting base disposed substantially at right angles with said spacing member one end of said lath seat bent upwardly.

2. In means of the character described, a spacing clip embodying a horizontally disposed supporting base, a vertically disposed spacing member supported by said supporting base, a lath seat supported by the upper end of said spacing member, and a cooperating nail disposed in parallelism with said spacing member and projecting through said lath seat and supporting base, one end of said lath seat bent upwardly thereby providing means functional for limiting the movement in a direction laterally away from said nail of lath wire seated on said lath seat.

3. In means of the character described, a spacing clip comprising a spacing member, a lath seat at the upper end of said spacing member, and a retaining lip at the intersection of said spacing member and lath seat.

4. In means of the character described, a spacing clip having a spacing member disposed in a vertical plane, the lower end of said spacing member terminating in a supporting base disposed in a horizontal plane, the upper end of said spacing member terminating in an upwardly extending loop forming a retaining lip, one end of said loop terminating in a horizontally extending lath seat.

In testimony of the foregoing being my own, I have hereunto affixed my signature this 11th day of March, 1924.

GEORGE F. VOIGHT.
